(57) **CLAIM**

The ornamental design for a yagi antenna, as shown.

DESCRIPTION

FIG. 1 is a top perspective view of an antenna carrier showing our new design;

FIG. 2 is a bottom perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof;

FIG. 8 is a bottom plan view thereof; and,

FIG. 9 is a top perspective view thereof mounted to a printed circuit board.

The broken line showing of an antenna element, leads, and printed circuit board is included for the purpose of illustrating environment and forms no part of the claimed design.
